UNITED STATES PATENT OFFICE.

JOSEPH H. VINEBERG, OF MONTREAL, QUEBEC, CANADA.

STRAP FASTENING.

Application filed June 24, 1926. Serial No. 118,234.

My invention relates to fastenings of the type consisting of a buckle and strap in which the strap may be passed around an object in either a single loop or in two loops disposed one at right angles to the other.

The object of the invention is to provide a new and improved fastening of this type having a wider range of adjustment of the strap relatively to the buckle than fastenings of this type heretofore in use.

A further object is to provide a simplified construction in which the end of the strap that is permanently connected to the buckle may be shifted to different positions relatively to the latter to adapt the fastening to various arrangements of looping, it being possible to loop the strap around an object in a single loop, or in a plurality of loops disposed at angles to one another.

For full comprehension of my invention, however, reference must be had to the accompanying drawings in which similar reference characters indicate the same parts, and wherein:

Figure 1 is a plan view of a rectangular package having my improved strap fastening applied thereto in a single loop;

Figure 2 is a similar view illustrating the fastening applied to the package in two loops disposed at right angles to each other;

Figure 3 is a detail view of the buckle drawn to a larger scale and showing the adjustability of the strap relatively thereto; and

Figure 4 is a detail view of a modified form of buckle unit.

Referring to the accompanying drawing my improved fastening consists of a strap indicated at 2 and a metallic unit connected to one end of the strap and comprising a buckle 3 and a closed loop 4 of semi-circular or D-form. In Figures 1-3 the buckle frame is shown as formed integrally with the loop, the straight side of the loop and the rear side of the buckle being constituted by a single cross bar 6 to which the ends of the curved side 7 of the loop and the parallel sides 8 and 9 of the buckle are united. The buckle frame is smaller in width than the loop and is preferably of rectangular form although not essentially so. Its front side 10 is disposed parallel to the bar 6 and constitutes a fixed jaw adapted to coact with a movable jaw 12 in gripping the free

end of the strap, such movable jaw consisting of a straight bar with a toothed side 13 having its ends 14 looped around and slidable on the buckle frame sides 8 and 9. 60

A keeper for the loose end of the strap is provided by a comparatively small rectangular loop 15 within the main loop and constituted by cross bar 6 and sides 16, 17, and 18. 65

The strap is adjustably connected to the semi-circular side 7 of the main loop in such a manner that it may be slidable shifted to any position on the arc of one hundred and eighty degrees represented thereby. The loose slidable connection of the present construction is obtained by folding the end 20 of the strap around the side 7 and back upon itself as at 21 where it is secured by stitching or riveting. 75

Figure 4 illustrates a modification in which the buckle frame is made separately from the loop and the two are flexibly connected, in this instance the loop being circular. 80

In the use of the improved fastening herein described when it is desired to pass the fastening around an object in a single loop the permanently connected end 20 is shifted to position "A" on the curved side of the loop at which point it is in alignment with the buckle jaws so that the tension of the two strap ends on the buckle unit is in opposite directions. When it is desired to pass the strap around the object in two loops 90 the end 20 is shifted to position "B" and the strap is looped around the object in parallelism with bar 6, following which it is passed through the loop and again looped around the object in a direction at right angles to the first loop, the end of the strap being secured in jaws 12 and 13. 95

If the shape of the object is irregular or if it is desired to arrange the loops in other positions than those indicated this may be done by shifting the end 20 to the position best suited for the arrangement and passing the strap through the loop as many times as the dimensions of the fastening will permit. 100

What I claim is as follows:

1. A strap fastening of the type described comprising a unit consisting of a buckle in which the free end of the strap may be secured and a closed loop of semi-circular form connected to the buckle, and a strap one end of which is slidably connected to the

2
curved side of the loop and adjustable to any position thereon within an arc of 180 degrees.

2. A strap fastening of the type described comprising a metallic unit consisting of a buckle in which the free end of the strap may be secured and a closed loop of D-form formed integrally with the buckle and of greater width than the latter, the rear side 5 of the buckle and the straight side of the loop being constituted by a cross-bar common to both, said buckle having straight sides, a fixed jaw formed integrally with said sides and disposed parallel to the cross-

bar, and a movable jaw having its ends 15 slidably mounted upon said buckle sides, a keeper consisting of a comparatively small loop formed integrally with said cross-bar and located within the first-mentioned loop, a strap having one end slidably connected 20 to the curved side of the first-mentioned loop and adjustable to any position thereon within an arc of 180 degrees.

In testimony whereof I have signed my name to this specification this twenty-first 25 day of June, 1926.

JOSEPH H. VINEBERG.
